COMBINED COMPRESSOR AND POWER CYLINDER

Werner F. Boldt, Overland, and Burns Dick, Ferguson, Mo., assignors to Wagner Electric Corporation, St. Louis, Mo., a corporation of Delaware

Application December 15, 1937, Serial No. 179,860

7 Claims. (Cl. 60—54.6)

Our invention relates to braking mechanism and more particularly to a power-operated compressor for hydraulically actuated brakes for vehicles.

5 One of the objects of our invention is to produce an improved combined hydraulic compressor and power cylinder which is compact and durable in construction, efficient in operation and easily mounted on a support of a vehicle.

10 Another object of our invention is to so construct a combined hydraulic compressor and power cylinder that when mounted on a support either the compressor or the power cylinder may be removed independently of the other for repair or replacement purposes without the necessity of removing the part which is secured to the support.

15 Still another object of our invention is to produce a combined hydraulic compressor and power cylinder in which the axes thereof are in alignment and vertically positioned and in which a non-splash reservoir for the compressor is so built into the dead space of the power cylinder that the overall length of the combination is a minimum.

20 Other and more specific objects of our invention will become apparent from the following description taken in connection with the accompanying drawings in which figure 1 is a vertical cross-sectional view of our improved combined hydraulic compressor and power cylinder; Figure 2 is a cross-sectional view taken on the line 2—2 of Figure 1; Figure 3 is a cross-sectional view taken on the line 3—3 of Figure 2; and Figure 4 is a side view showing the mounting arrangement and other exterior details.

25 Referring to the drawings in detail, the reference character 1 indicates the central mounting member of the combined compressor and power cylinder, 2 the cylinder of the compressor unit, and 3 the cylinder of the power cylinder unit. The member 1 is formed with an annular flange 4 to which is detachably secured the flanged end 5 of the cylinder 3 by means of suitable bolts 6. The lower end of the central member 1 is formed with an opening through which a portion of cylinder 2 is adapted to project, the cylinder being attached to the member by means of a flange 1 and securing bolts 8. 30 One side of the central member 1 is formed with an integral attaching portion 9 having a flat surface 10 and bolt receiving openings 11 whereby unit 1 can be secured to any convenient supporting member on the vehicle.

35 The central mounting member 1 is also formed

with a liquid containing reservoir 12 for the hydraulic compressor. This reservoir projects upwardly into the lower end of cylinder 3 of the power cylinder. The reservoir comprises a plurality of separate compartments 13 (see Figure 2) formed by radial partitions 14 extending inwardly to a point adjacent the upper end of cylinder 2. The top wall of the reservoir is dished or recessed and is provided with a central opening 15 aligned with the lower opening. In order to provide free communication between the several compartments 13 of the reservoir, the lower inner edge of each partition 14 is cut away as indicated at 16 (Figure 1). The top dished wall of the reservoir is also provided with a plurality of holes 17 for permitting free passage of air to and from the top part of the several compartments of the reservoir.

40 The compressor cylinder 2 has reciprocable therein a piston 18, the forward end of which is provided with a suitable packing cup 19 to prevent leakage past the piston during its forward stroke. The piston is normally held in its retracted position against the stop 20 by means of a coil spring 21 interposed between the head end of the piston and the forward end of cylinder 2. The forward end is adapted to be connected by means of a suitable conduit 22 to the braking assemblies (not shown) to actuate the brakes thereof when fluid is forced out of cylinder 2 by movement of the piston. The wall of the portion of the cylinder within the reservoir, at a point just forward of the packing cup 19 when the piston is in its retracted position, is provided with several compensating ports 23 (Figure 3) in order that any expansion and contraction of the liquid in the system may be compensated for. These ports also permit any excessive fluid in the system to return to the reservoir after the piston has assumed its retracted position.

45 The head of the piston is formed with a plurality of annularly spaced passages 24 which extend from the head surface of the piston to the chamber 25 at the rear of the piston formed by the piston skirt. This chamber is adapted to be in constant communication with the fluid in the reservoir by means of a passage 26 in the skirt of the piston and an annular groove 27 in the wall of the cylinder, the latter communicating with one or more of the chambers 13 of the reservoir through one or more openings 28 (see Figure 3). The piston is also formed with a longitudinal extending groove 29 which communicates with passage 26 to insure that this

passage will be in communication with groove 27 in the forward position of the piston.

The construction just described insures that fluid at all times will be at the rear of the piston, especially in the chamber thereof. Thus, if during the retractile stroke of the piston following a protractile stroke there should be a tendency to create a subatmospheric pressure in the system, liquid will be free to flow from the 10 rear side of the piston through passage 24 and past the lip of packing cup 19 to overcharge the system.

The cylinder 3 has reciprocably mounted therein a piston 30 provided with suitable packing rings 31. The piston is formed with pressed metal and is of dished formation to lend strength to the piston. The upper wall of cylinder 3 is also dished as shown in Figure 1 in order that the space between the piston and the end of the cylinder will be a minimum when the piston is in its fully retracted position. The outer edge of the piston also carries a bumper ring 32 for engaging the end of the cylinder. The top wall of the cylinder has mounted thereon a suitable fitting 33 whereby a conduit 34 may be connected thereto so that air under pressure may be admitted to the cylinder from some suitable source, as for example, a storage tank.

The piston 30 has secured thereto a piston rod 35 which extends through the opening 15 in the dished top of the reservoir and abuts piston 18 of the compressor. The lower end of this piston rod is semi-spherically shaped and is adapted to cooperate with a semi-spherical recess in the rear side of the piston head. A retractile spring 36 surrounds the piston rod 35 and at its lower end engages the bottom of a cup-shaped member 37 extending through opening 15 in the dished top of the reservoir and to a point adjacent the head 40 of piston 18 when it is in its retracted position. The upper end of this cup-shaped member 37 is formed with an annular flange 38 which covers the dished portion of the reservoir top to form a chamber which is in communication with the 45 compartments 13 by means of openings 17. The lower end of the cup-shaped member 37 also carries a guiding and packing member 47 for the piston rod.

Since the volume of cylinder 3 below piston 30 will vary as a result of movement of the piston, provision is also made to permit air to be expelled and drawn into this portion of the cylinder. The central mounting member 1 has formed therein openings 39 (Figure 2) which enter a chamber 40 formed in the mounting portion 9. This chamber is filled with a suitable air cleaning material and is open on its lower side to the atmosphere by means of a plurality of openings 41 (dashed lines in Figure 2).

60 Provision is also made for a breather opening for the several compartments of the reservoir. Referring to Figure 3, this is accomplished by means of a tubular member 42 extending from the exterior through one of the compartments 13 and into the chamber formed by the dished top wall of the reservoir and the cup-shaped member 37. The lower end of this tube 42 is screwed into the wall of member 1 and is provided with a chamber 43 containing air cleaning material 44.

70 The reservoir is adapted to be filled through a suitable spout 45 which is formed integrally with member 1 and extends outwardly to a point beyond the attaching flanges 4 and 5. A closure plug 46 is provided to close and seal the end of 75 the spout.

Referring to the operation of the above described combined compressor and power cylinder, reservoir 12, cylinder 2, and the braking system connected thereto are all first filled with a suitable liquid. When it is desired to apply the 5 brakes, the air under pressure is admitted to the power cylinder through conduit 34 by means of a suitable control valve not shown. This will cause piston 30 to move downwardly, forcing ahead of it piston 18 of the compressor. As soon as the lip 10 of cup 19 passes the compensating ports 23, the liquid in the braking system will be placed under pressure and the brakes applied. When it is desired to release the brakes, the air is exhausted from the power cylinder and spring 36 returns piston 30 to its normally retracted position as shown in Figure 1. Simultaneously spring 21 for the 15 compressor piston 18 causes this piston to return to its retracted position. If the return of piston 18 is more rapid than the return of liquid from the 20 braking system into cylinder 2, there will be created in this cylinder a subatmospheric pressure which will cause liquid to pass from chamber 25 at the rear of piston 18 to cylinder 2 by way of passage 24 and then past the lip of the 25 packing cup 19. When piston 18 returns to its retracted position, this excess of liquid in cylinder 2 will be free to return to the reservoir through the compensating port 23. Since piston rod 35 only abuts piston 18, piston 30 of the 30 power cylinder is always free to return independently of the compressor piston 18. Also by not having piston rod 35 secured to piston 18, any tendency of piston 30 to become slightly tilted by operation will not produce any unreasonable side binding of piston 18 in cylinder 2. 35

The particular construction of the combined power cylinder and compressor is such that the power cylinder may be removed from the central mounting member 1 without the necessity of also removing the member from the support. Thus, if it is necessary to repair or replace any part of the power cylinder, such can be done without affecting the compressor. Likewise, the compressor unit may be removed from the mounting member 1 without removing the member from the support, thereby enabling repair and replacement of parts of the compressor without disturbing the power cylinder. The particular construction of the reservoir is also another important feature. The several compartments prevent any undesirable surge of the liquid in the reservoir when the vehicle is accelerated or decelerated. The openings 16 at all times permit the several compartments to freely communicate with each other. The small holes 17 also assist in damping the surging of the liquid for when excess liquid is forced into one of the compartments, it must in turn force air out of this compartment into the other compartments through these passages. The positioning of the reservoir between piston 30 of the power cylinder and the upper end of the compressor cylinder utilizes the dead space in the power cylinder and thus results in a compact construction with a minimum overall length. The breather tube 42 also insures that clean air can flow into the top of the compartments of the reservoir at all times, thus keeping the liquid free from any harmful foreign matter. The air which enters the power cylinder as a result of its movement is also thoroughly cleaned by the 60 cleaning material 44. 65

70 Being aware of the possibility of modifications in the particular structure herein described without departing from the fundamental principles 75

ples of our invention, we do not intend that its scope be limited except as set forth by the appended claims.

Having fully described our invention, what we claim as new and desire to secure by Letters Patent of the United States is:

1. In apparatus of the class described, a member provided with a reservoir having aligned openings in its ends, a cylinder detachably secured to one end of the member and having a portion of its length projecting into said reservoir through one of said openings, a piston in said cylinder, said piston when in retracted position being positioned in the projecting portion of the cylinder, a second cylinder secured to the other end of said member, a piston in said second cylinder, a piston rod secured to said second named piston and projecting through the other opening of said reservoir and operatively engaging the first named piston, a sleeve carried by the member and having a piston rod guide portion positioned within the portion of the first named cylinder which projects into the reservoir and adjacent the retracted position of the piston therein, and a coil spring surrounding the piston rod and interposed between the second piston and the guide portion of the sleeve.

2. In apparatus of the class described, a mounting member provided with a reservoir, partitions in said reservoir for driving it into a plurality of chambers, means for placing the chambers in communication with each other, a cylinder detachably secured to one end of the member, a piston mounted in said cylinder, means placing the reservoir chambers in communication with the cylinder when the piston is in retracted position, a second cylinder axially aligned with the first cylinder and detachably connected with the other end of the member, a piston in the second cylinder, and a piston rod extending through the top of the reservoir and operatively connecting the two pistons.

3. In apparatus of the class described, a member provided with a reservoir, a cylinder detachably secured to one end of the member and having a portion of its length projecting into said reservoir, said reservoir having a plurality of radially positioned partitions forming with the portion of cylinder therein a plurality of fluid containing chambers, means for interconnecting the chambers, a piston in the cylinder, means for placing the cylinder in communication with the chambers when the piston is in retracted position, a second cylinder detachably secured to the other end of said member and receiving a portion of the reservoir, a piston in the second cylinder, and a piston rod connecting the two pistons whereby when said second piston is subjected to differential fluid pressure the first named piston will be actuated.

4. In apparatus of the class described, a mounting member provided with a liquid containing reservoir having an opening in its top, said reservoir having partitions for dividing it into a plurality of compartments, a cylinder detachably secured to the lower end of the mounting member, a piston mounted in said cylinder, means placing the compartments in communication with each

other, means placing the compartments in communication with the cylinder when the piston is in retracted position, a second cylinder detachably secured to the other end of the mounting member, a piston in said cylinder, a piston rod extending through the top of the reservoir and operatively connecting the two pistons, means forming a chamber above the reservoir compartments, and means for placing said chamber in communication with all the compartments.

5. In apparatus of the class described, a mounting member provided with a reservoir having an annular flange surrounding the intermediate portion of the reservoir, said reservoir having an opening in its bottom and a recessed top provided with an opening axially aligned with the bottom opening, a cylinder detachably secured to the lower end of the member and having a portion projecting into the reservoir through the bottom opening in the member, means comprising radial partitions in the reservoir and the portion of the cylinder therein forming a plurality of liquid containing compartments, a piston in the cylinder, means placing the cylinder in communication with all the liquid containing compartments in the reservoir when the piston is in retracted position, a second cylinder detachably secured to the annular flange of the member, a piston in said second cylinder, a piston rod operatively connecting the last named piston with the first named piston and extending through the top opening of the member, a cup-shaped member extending through the top opening of the reservoir in surrounding relation with the piston rod and having a flange covering the recessed top of the reservoir to form a chamber, a coil spring surrounding the piston rod and interposed between the second named piston and said cup-shaped member, and means for placing said chamber in communication with all the fluid containing compartments of the reservoir.

6. In apparatus of the class described, a substantially vertically positioned cylinder, a piston reciprocable therein, a member forming a liquid containing reservoir in surrounding relation with the upper portion of the cylinder, said member being provided with a plurality of compartments, means for placing the compartments in communication with the cylinder when the piston is in its retracted position, means forming a chamber above the several compartments and communicating with each of said compartments by a restricted passage, and means for reciprocating the piston.

7. In apparatus of the class described, a chambered member provided with an opening in its bottom, a cylinder having a portion projecting through the opening of said member and secured thereto, said member being provided with a plurality of radially positioned partitions extending from the cylinder wall therein to the wall of the member and forming a plurality of liquid containing compartments, means for placing the compartments in communication with the cylinder when the piston is in retracted position, and means for reciprocating the piston.
